UNITED STATES PATENT OFFICE.

ANDREWS ALLEN, OF GLENCOE, ILLINOIS, AND DANIEL F. LEPLEY, DECEASED, LATE OF CONNELLSVILLE, PENNSYLVANIA, BY PAUL V. LEPLEY, EXECUTOR, OF CONNELLSVILLE, PENNSYLVANIA, ASSIGNEES OF ONE-HALF TO ALLEN & GARCIA CO., OF CHICAGO, ILLINOIS, A CORPORATION OF ILLINOIS, AND ONE-HALF TO THE CONNELLSVILLE MFG. & MINE SUPPLY CO., OF CONNELLSVILLE, PENNSYLVANIA, A CORPORATION OF PENNSYLVANIA.

SKIP-LOADING GATE.

Application filed May 13, 1927. Serial No. 191,208.

This invention relates to automatic skip loading apparatus and has particular reference to a cut-off gate with a spout for use in loading skips in mining operations in measured amounts.

An object of the invention is the provision of means whereby a hoisting skip may be automatically filled with lading without attention on the part of an operator, when the same reaches the bottom of a mine shaft.

Another object of the invention is the provision of skip loading means for automatically filling a skip with material to a predetermined height in the skip, thus uniformly loading every skip automatically and in equal amounts without necessity for personal attention to the loading thereof.

A still further object of the invention is to provide means for delivering material from a bin to a skip in measured quantities.

Another object of the invention is the provision of skip-loading means for rapid filling of the skip with a minimum amount of breakage to the lading.

Another object of the invention is the provision of means for safely locking all of the members in closed position of the gate without the aid of auxiliary means such as latches or the like.

Generally speaking the preferred embodiment of the invention comprises a bin having a chute leading from an opening therein, with a cut-off gate pivoted to said chute in a manner to be oscillated about said pivot for closing and opening the chute. In connection with the gate a spout is provided for delivering material from the chute into a skip. The inclination of the chute and of the spout on the gate is such that every skip load of material is approximately equal, this being accomplished by the angle of repose of the material delivered to the skip in conjunction with the inclination of the chute and the spout. Other features include mechanism for automatically opening and closing the gate as the skip is moved to loading position, everything being automatically done, thus eliminating the need of personal supervision and operation at the bottom of the shaft by an attendant.

The above recited and other objects of the invention will be more fully and better understood by reference to the accompanying specification and drawings and will be particularly pointed out in the appended claims.

In the drawings:

Fig. 1 is a side elevational view of the invention, with certain parts in vertical section, showing one form of the invention with a skip at the lower end of the shaft, and

Fig. 2 is a view similar to Fig. 1, showing a modification of the gate with the spout mounted thereon so as to be movable with respect thereto, also including a wiring diagram and diagrammatic representation of the manner of actuating the gate for loading purposes.

10 designates a mine shaft and particularly the lower end thereof, in which is shown the usual hoisting skip 11 operated therein in the usual manner. A bin 12 is provided into which the mined material is discharged adjacent the lower end of the shaft. In the drawings the bin is shown as having sloping bottom walls 13 and 14. The wall 14 has therein a discharge opening 15. The bin may be supported in any desirable manner, such as by a suitable outer wall 16 and foundation 17. A discharge chute 18 is secured to the wall 14 of the bin, adapted to direct material from the opening 15 in said wall, this chute comprising the usual bottom and side walls. An end gate A for said chute with its end wall arcuate is rotatably supported on a shaft 20 suitably secured to the under side of the discharge chute 18. One means for holding the gate closed is the provision of a toggle link connecting the piston of the gate-operating cylinder with the gate so that when the gate is in closed position, the link assumes a position practically normal to the guideway, thus preventing without a latch or equivalent means, the spout from falling back into the shaft if the fluid pressure in the cylinder should be cut off. In Fig. 1, the gate A is shown as comprising an arcuate end member 19 and side wall 19^a with a spout 21 extending outwardly from the upper end of the end member 19 of the gate for projecting into the skip 11 for loading purposes. The side walls of the spout

100

are coincident with the side walls 19^a of the gate. When the gate is open, the spout 21 serves as a continuation of the chute 18, the angle of inclination of which chute and spout 5 is such that the material delivered thereover to the skip 11 is regulated by the angle of repose of the material with relation to the chute, spout and the material in the skip. In order to control the speed of outflow from the bin 10 12, a slidably mounted door 22 is provided for the opening 15. In Fig. 1 this door is shown as operated by a rack bar 23 secured thereto, which is in engagement with a gear wheel 24 controlled by a hand wheel 25 which 15 members are suitably mounted on a bracket 26 secured to a beam 27 on a supporting structure 28 resting preferably on the foundation 17. Operation of the hand wheel 25 regulates the position of the door 22 so that flow of material through the opening 15 may be adjusted from time to time as conditions require. We do not wish, however, to be limited to this 20 particular means for actuating the door 22, as any other suitable means will be sufficient for 25 the purpose intended. A similar door may be used with the arrangement of Fig. 2.

For opening the gate A a horizontally disposed cylinder 29 is suitably mounted on the foundation 17 at any place convenient to the 30 gate A and the other parts of the mechanism. A piston 30 operated from the cylinder 29 is connected to a cross-head 31 mounted in a guide-way 32 on the foundation 17, which cross-head 31 is connected by means of a link 33 to a pivot 33^a on the gate A. It will be noted that the parts are so arranged that the link 33 assumes a substantially normal position to the guideway when the gate is closed. In other words the link 33 and the piston 30 40 form a connection whereby the gate is securely locked in closed position thus eliminating latches or other fastening means which have been employed heretofore and which are readily disarranged. As one means for operating the piston 30 of the cylinder 29 to actuate the gate A, we may employ fluid pressure, in which event there are connected to the 45 ends of the cylinder 29 supply pipes 34 and 35 leading to a four-way valve 36 controlled 50 by a valve handle 37, with an outlet pipe 38 leading from the four-way valve to a sump at the bottom of the shaft, into which water or other fluid used in the operation of the cylinder is discharged. A fluid supply pipe 39 is 55 provided leading from a suitable source of supply (not shown) to a manifold 40 having an air hammer 41 connected thereto by means of a pipe 42, with a connection 43 from the manifold to the four-way valve 36, the manifold 40 and the air hammer 41 being used for 60 the purpose of maintaining a predetermined steady pressure for the operation of the piston 30 in the cylinder 29 during the actuation of the gate.

65 We use the term "fluid" pressure herein in

a broad sense as including air, liquid or any similar agency suitable for carrying out the purpose of our invention.

As one means for actuating the four-way valve 36, we provide a solenoid 44, the armature of which is connected to the arm 37 of the valve 36. In Fig. 1 the solenoid 44 is shown as provided with lead wires 45 and 46 from a time limit relay 47, in which leads a switch 48 is connected, having push buttons 49 and 50 therein, by means of which the operation of the solenoid 44 may be manually controlled if desired.

Adjacent the shaft 10 is a hatchway switch 52 mounted on a supporting member 51, having an arm 53 projecting outwardly therefrom, adapted to be engaged by a suitable member on the skip 11, such as a bracket 54, so that the switch 52 may be actuated with every lowering and hoisting of the skip 11. From the switch 52 a conductor 55 extends to a source of energy, such as a battery 56, from the opposite side of which a conductor 57 leads to a manually operated cut-out switch 58, thence to the solenoid 44, the solenoid 44 and the switch 52 being grounded, so that an electric circuit is established through the solenoid whenever the circuit is closed by switch 52, thus controlling the operation of the four-way valve 36. Connected to 95 a commutator on the hub of the gate A are lead wires 60 and 61, which lead to a signal 62 in the hoist house, whereby a signal may be given the hoisting engineer to advise him of the position of the gate with respect to the 100 skip.

In the operation of the device shown in Fig. 1, the skip 11 is lowered in the shaft 10 and as it reaches the bottom of the shaft the bracket 54 thereon actuates the arm 53 of the switch 52, establishing a circuit through the solenoid 44, whereupon the four-way valve 36 is actuated to move the gate A into full line position shown in Fig. 1. Operation of the valve 36 in this manner admits pressure to the left end of the cylinder 29, opening the right end of the cylinder for exhaust, thus moving the piston to the right as viewed in this figure, so that any fluid in the right end of the cylinder is discharged into the sump through the pipe 38. When the gate A is thus opened, material will flow from the bin along the chute 18 over the spout 21 into the skip 11, filling the skip to such position as is determined by the angle of repose of the material with respect to the inclination of the chute 18 and the spout 21. In the meantime a circuit has been established through the time limit relay 47, which relay has been set to operate at a predetermined interval corresponding to the time needed for material to completely fill the skip 11, whereupon said relay operates to break the circuit from switch 52 to the solenoid 44, causing the valve 36 to operate to admit pressure to the right end of the 110 115 120 125 130

cylinder 29 and to open the left end of the cylinder to exhaust, thereupon moving the gate A upwardly into closing position, that is in position when the arcuate wall 19 there-
 5 of covers the end of the chute 18, whereupon the flow of material to the skip is cut off and any material in the spout returned to the chute and the spout 21 is accordingly turned out of the path of the skip 11, as shown in
 10 dotted lines in Fig. 1. In the meantime the hoisting engineer has received a signal at 62 that the skip is ready to be hoisted. As he hoists the skip, the bracket 54 thereon, moves the arm 53 of the switch 52 into open circuit
 15 position, ready to be actuated by the downward movement of the skip on its next trip.

The rate of discharge through the opening 15 is controlled by the position of the sliding door 22 and the inclination of the chute 20 18 and spout 21, which rate of discharge is determined prior to the actual operation of the device and the amount of material delivered into a skip being determined by the angle of repose of the material and the inclination of the chute 18 and spout 21, it being uniform with every skip full of material, thus making possible the loading of material from the bin 12 into skips, which loads are the same in amount without requiring the presence of an attendant. We utilize the angle of repose of the coal or other material being loaded into the skip of our invention for controlling the flow of material into the skip. The angle of repose of 35 coal, for instance, on steel is one thing and of coal on coal is another, the latter angle being greater than the former. Hence as the coal or other material is delivered into the skip and as the angle of repose of this material is reached, further flow of the material into the skip will cease for this reason, there-
 40 upon blocking further flow of the material along the chute. Thus the material itself is utilized to stop its own flow in the manner just described. As the gate is moved in a closed position, any surplus material in the chute of the gate of Fig. 1 will be discharged onto the top of the material in the skip 11, until the angle of repose of the material in
 45 this chute is reached, whereupon the flow stops and any excess material in this gate chute will be allowed to fall back into the chute 18. Likewise with respect to the arrangement of Fig. 2 as the spout C is raised in the manner hereinafter described, the flow of material therealong will taper off until the angle of repose of the material with respect to this chute is reached, whereupon the flow will stop and any excess material remaining 55 in this spout will fall back into the chute 18 when the spout is moved to closed position. By reason of the arrangement of parts just described, the skip will not overflow even though the flow should not be cut off promptly by actuation of the gate. A hand control
 60

switch 58 is interposed in the solenoid circuit so that the device operates automatically as long as the switch is closed and the skip is raised and lowered in the usual manner.

In Fig. 2 of the drawings, a cut-off gate 70 B is shown, pivoted at 20 to the under side of the chute 18, leading from the bin 12, in the same manner as described with reference to Fig. 1. In this modification, a spout C instead of being secured to the gate, as in Fig. 75 1, is pivoted to gate B at 65, so as to have limited angular movement with respect to the gate B. This is for the purpose of loading the skip 11 with more material than is possible with the form shown in Fig. 1 and to 80 accomplish this object more rapidly and with less breakage to the lading. In the preferred embodiment of this invention, the loading side of the skip is arranged to slope at an angle of approximately 30° to the vertical, 85 the bottom of the skip being rounded on a long radius. It will be noted from Fig. 2 that the bottom of the spout C when in its lowermost loading position is substantially parallel with the sloping side of the skip 11. 90 It is evident therefore that material will flow from the bin to the skip more rapidly and with less breakage than if it were allowed to flow in a mass down the spout, falling to the bottom of the skip. With the arrangement 95 as shown in Fig. 2 at the beginning of the loading of the skip, the lading will slide down the sloping side wall of the skip from the chute until it encounters the curved bottom, thus preventing such impact with the steel 100 sides or bottom of the skip as to break the lading. Furthermore, since the spout C in its extreme low position in loading is substantially parallel to the sloping sides of the skip, the material comes down along the skip 105 side in a mass so that any fine material therein will tend to cushion the larger lumps. As the mass of material in the skip fills up to a point substantially even with the end of the spout C in its loading position, the spout C 110 will be caused to rise slowly at a predetermined and adjustable rate, so that the end of the spout will remain always slightly above the top of the pile of lading in the skip. At the end of its upward travel in this position, the chute C will lie at or near the angle of repose of the material in the spout so that the flow of material will be reduced in amount 115 and speed and will entirely cease, stopped by the angle of repose of the material in the skip having been reached, resulting in that the pile of lading in the skip will have been brought up to the maximum possible height with the minimum amount of drop throughout all parts of the loading cycle. In Fig. 2, cylinder D is provided for actuating the gate B and another cylinder E for actuating the spout C pivoted to the gate B. These cylinders are preferably horizontally disposed and suitably secured to the foundation or 120 125 130

superstructure underneath the bin 12 in suitable position to function properly.

Cooperating with the cylinder D is a piston rod 30 connected to a cross head 31 with a link 33 pivotally connected to the gate B at 33^a. The cylinder E is provided with a piston rod 30^a, crosshead 31^a with a link 33^b extending from the cross head 31^a to a pivot 33^c on the spout C.

10 For actuating the cylinder D a four-way valve 36 is provided having a valve handle 37 actuated by a solenoid 44. A supply pipe 39 extends to the four-way valve 36 from any suitable source of fluid pressure. At each 15 end of the cylinder D we provide control elements. Each of these elements comprises branch pipes 66 and 67, the pipe 66 being formed for intake and the pipe 67 for exhaust. In the branches 66 are interposed 20 check-valves 68 and globe valves 69, while in the branches 67 are similar check-valves 70 and globe valves 71, the check-valves 68 being positioned to permit flow in but one direction through the branches 66, and the 25 check-valves 70 permitting flow in the opposite direction only through branches 67. The purpose of the valves 69 and 71 is to regulate the speed of operation of the gate B by cutting down either the flow in the intake or the 30 exhaust. This same arrangement is used for regulating the flow of fluid in the valves connected with cylinder E, which regulate spout C. If air is employed as a fluid pressure medium, such regulation will be obtained by 35 closing the exhaust so that full pressure will remain on the piston at all times as a varying load on the gate will not materially affect the speed of operation of the various parts.

40 With respect to cylinder E similar branch connections are provided as indicated at H and K. Each of these connections comprises similar branches 66 for intake and 67 for exhaust with similar check and globe 45 valves as indicated with reference to cylinder D. For controlling cylinder E a four-way valve 36^a, similar to valve 36 is provided, having a lever 37^a actuated by solenoid 44^a. A branch of the supply pipe 39 leads to the 50 four-way valve 36^a and from each of the valves 36 and 36^a in Fig. 2 exhaust connections 38^a lead to a common exhaust 38 as described with reference to Fig. 1.

55 Referring to the wiring diagram shown in Fig. 2, there are present two main conductors L₁ and L₂ leading from a source of energy.

A hatchway switch 53^a is suitably supported 60 near the lower end of the shaft 10 which is normally open. A bracket 54^a on the skip 11 is positioned to close the hatchway switch 53^a when the skip reaches its lowermost position in the shaft. Another hatchway switch M is positioned to be actuated by the crosshead 65 31 of the cylinder D. This switch includes an

arm 72 connected to a binding post 73 for cooperating with a contact 74. This switch M is normally open. Another hatchway switch N is positioned to be actuated by a projection 31^b on the piston 30^a of the cylinder E. This switch comprises an arm 75 connected to a binding post 76 and a contact member 77. This switch is normally closed.

Another hatchway switch O is positioned 75 to be actuated by the cross head 31 of the cylinder D when the gate B is closed. This switch comprises an arm 78 connected to a binding post 79, and with a contact 80. This hatchway switch is normally open.

80 A contactor P with which cooperates a solenoid 81 has two arms 82 and 83 communicating with connections 84 and 85 respectively, adapted under certain conditions to engage contacts 86 and 87. A time limit relay Q is provided having an armature 88 carrying a contact plate 89 adapted under certain conditions to bridge the gap, between the contacts 90 and 91.

90 The circuits controlled by the various switches and operating the several mechanisms of the invention are as follows:

Circuit I.

95 When the skip 11 reaches the bottom of the shaft 10, the projection 54^a thereon closes the hatchway switch 53^a whereupon a circuit is established from the conductor L' through connection 100, conductor 101, contact 53^c, arm 53^a, contact 53^b, conductor 102, connection 103, conductor 104 to switch N which is closed, through contact 77, arm 75, binding post 76, conductor 105 to solenoid 44 through conductor 106 to connection 107 in L₂. This circuit energizes the solenoid 44, whereupon 100 the arm 37 of the four-way valve 36 is moved to admit pressure to the cylinder D to open the gate, that is, move it from the dotted line position in Fig. 3 to the full line position. When the gate is closed, that is in the dotted 110 line position, the piston 30 of the cylinder D is at its limit of travel to the left as viewed in this figure, with the parts as shown in dotted lines. Actuation of the four-way valve 36 thereupon admits pressure to the left-hand end of the cylinder D opening the right-hand end thereof to exhaust, whereupon the gate is moved downwardly into the full line position of Fig. 2. Movement of the piston 30 of the cylinder D to the full line position 115 closes the switch M bringing the arm 72 thereof against the contact 74 whereupon a circuit is established as follows:

Circuit II.

120 Main line, L', connection 100, conductor 108, connection 109, conductor 110, binding post 73, arm 72, contact 74, conductor 111, connection 112, solenoid 81, conductor 113, connection 114, to the main L₂. This circuit 125

energizes the solenoid 81 therefore closing the contactor P, that is, moving the arms 82 and 83 thereof against contacts 86 and 87, establishing two other circuits as follows:

5 *Circuit III.*

From main L', connection 100, conductor 101, hatchway switch 53^a, conductor 102, connection 103, conductor 115, contact 87, arm 83 of the contactor P, through connection 85, conductor 116, connection 112, solenoid 81, conductor 113, connection 114, to line L₂. This circuit maintains the contactor in closed position when the establishing circuit just heretofore described is broken. The second circuit established on the closing of the contact B is as follows:

10 *Circuit IV.*

20 Main L', connection 100, conductor 108, connection 109, conductor 117, connection 118, conductor 119, to contact 86 of the contactor P, arm 82, connection 84, through the time limit relay Q to line L₂ at connection 114. This circuit energizes the time limit relay Q. Energization of this relay bridges the gap between contacts 90 and 91, establishing a circuit as follows:

25 *Circuit V.*

30 Line L', connection 100, conductor 108, connection 109, conductor 117, connection 118, conductor 120, contact 90, contact plate 89 of the relay Q, contact 91, conductor 121 to solenoid 44^a and conductor 122 to line L₂. This energizes the solenoid 44^a controlling the operation of the spout cylinder E.

Having in mind the circuits as heretofore recited, the closing of the circuit No. 40 I through the hatchway switch 53^a energizing solenoid 44, causes the gate B to open. When the gate reaches fully opened position, the hatchway switch M is closed as heretofore recited, closing the contactor P, and establishing a circuit through the time limit relay Q. After a predetermined period, said time relay Q operates to complete the circuit No. V through contacts 90 and 91 thereof, actuating the solenoid 44^a controlling the operation of cylinder E connected to the spout C, whereupon fluid pressure is admitted to the left end of the cylinder E and the spout C raised to the substantially horizontal dotted line position shown in Fig. 2. 45 When this spout C reaches its substantially horizontal position as just described, the hatchway switch N is opened breaking the circuit through solenoid 44. Thereupon the armature drops admitting pressure to the right-hand end of the cylinder E and opening the left-hand end to exhaust, thus raising the gate B to closed position, that is, the position shown in dotted lines in Fig. 2. Movement of the piston 30 of the cylinder D from full line to dotted line position

5 opens the hatchway switch M and closes the hatchway switch O. The circuit controlled by the hatchway switch O is the signal circuit to the hoisting engineer. This circuit is suitably connected through the conductors 123 and 124 with the hatchway switch O and a signal (not shown) in the hoist house. When the switch O is closed, the signal is given, whereupon the hoisting engineer hoists the skip 11. Hoisting the skip 11 10 opens the hatchway switch 53^a thereupon breaking the circuit to the connection 115. In the meantime the time limit relay Q has functioned to break the connection between the contacts 90 and 91, thus opening all of 15 the circuits which have heretofore been described with the exception of the signal circuit. When the solenoid 44^a is deenergized by the breaking of the circuit controlled by the time limit switch Q the armature of 20 said solenoid drops, admitting pressure to the right-hand end of the cylinder E and opening the other end to exhaust, whereupon the spout C is moved to its downmost position with respect to gate B, which is the position shown in full lines in Fig. 2, but while the gate is in closed position.

25 By raising the spout C as the lading is being discharged from the bin 12 into the skip 11, the discharge thereof is tapered off as 25 the angle of flow is decreased and the spout being moved to the dotted line horizontal position of Fig. 2 tends to fill the skip with more material than as in the form shown in Fig. 1 of the drawings where the spout 30 is rigidly secured to the gate.

35 With the foregoing operations clearly in mind, it will be apparent that material discharged from the bin 12 will, by reason of the inclination of the chute 18 and the spouts attached to the end gate, assume a certain angle of repose. In the form shown in Fig. 1 the material will not fill the skip as completely as in the form shown in Fig. 2, for the reason that the spout C in Fig. 2 is 40 raised relatively to the gate B tapering off the flow and also directing material above the line of the material possible with the arrangement of Fig. 1. In either case, however, successive skip-loads of material will be 45 the same, whichever form of the invention is used. It will therefore be apparent that we have provided mechanism for loading skips in mine shafts, so that every skip load will be the same as every other skip load without the attention of an operator or attendant at the lower end of the shaft. It is manifest that such an arrangement will decrease the cost of loading skips by reason of the elimination of the attendant. With the mechanism shown in Fig. 2, we have provided a 50 faster means of filling the skip to a greater capacity than has heretofore been accomplished with other arrangements, also with a minimum amount of drop so that the break- 55

age of friable lading will be less than if the material were dropped from a fixed loading point, giving approximately the same total capacity of the skip.

5 While we have shown and described certain details of construction, we do not wish to be understood as limiting ourselves thereto, as we contemplate changes in form and the proportion of parts and the arrangement 10 of the apparatus as circumstances may suggest or render expedient, without departing from the spirit of our invention.

We claim:

1. In a mechanism of the class described, 15 in combination, a skip, means for delivering material into said skip, a cut-off gate associated with said delivery means, a spout on said gate movable with respect thereto, power means for operating said gate, other power 20 means for operating said spout, and means actuated by the movement of said skip for controlling the power means associated with said gate and with said spout.

2. A hoisting mechanism, including in 25 combination, a skip, means for discharging material into said skip, a cut-off gate associated with said discharge means, power mechanism for operating said gate, said mechanism including fluid pressure devices 30 and electrically actuated controls for causing delayed action of said devices, the actuation of the controls being initiated by movement of said skip.

3. A skip hoisting mechanism, including in 35 combination, a skip, a chute for discharge into said skip, an oscillating end gate for the chute, a spout carried by the gate and movable with respect thereto, power mechanism for actuating the gate, other power mechanism for actuating said spout, and means for 40 controlling said spout actuating means including a solenoid with a time limit relay included in said solenoid circuit.

4. A skip hoisting mechanism, including 45 in combination, a skip, a chute for delivering material to said skip, an end gate for said chute pivoted thereto for oscillation in a vertical direction, a spout carried by said gate, means for oscillating said gate including a fluid pressure device, a valve for regulating 50 admission and discharge of fluid to said device, means for operating said valve including a solenoid, a circuit for said solenoid including a switch, and means on said skip for controlling said solenoid circuit, whereby on 55 movement of said skip in one direction, said gate may be opened to discharge material into said skip and a time limit relay in said circuit for causing said solenoid to move said valve to close said gate after a predetermined 60 interval, and means for indicating at a position remote from the chute the angular position of said gate.

5. A skip hoisting mechanism, including in 65 combination, a skip, a bin, a chute leading

outwardly from said bin, said bin having an opening therein adjacent said chute, a closure for said opening, means for moving said closure to vary discharge through said opening, an end gate for said chute pivoted thereto for oscillation in a vertical direction, a spout carried by said gate adapted when in open position to lie at substantially the same inclination as said chute bottom, fluid pressure means for operating said gate, a valve for said means, and a control means for said valve including a solenoid and a circuit therefor with a time limit relay interposed therein, and means actuated by the movement of said skip for closing said solenoid circuit. 70 80

6. In a mechanism of the class described, in combination, a skip, a chute for discharging material therein, an end gate for said chute pivoted thereto and adapted for vertical oscillation, a spout carried by said gate for projecting into said skip under certain conditions, fluid pressure means for actuating said gate, a valve for controlling said fluid pressure means, and connections between said valve and said means including devices for regulating the flow between said valve and said fluid pressure device, means for regulating said valve including a solenoid and a switch in said solenoid circuit adapted to be closed by said skip in its downward movement. 85 90 95

7. A skip hoisting mechanism including in combination, a skip, a chute for delivering material to said skip, an end gate for said chute adapted for oscillation in a vertical plane, means for operating said gate including a fluid pressure cylinder, a four-way valve connected thereto, a solenoid for actuating said valve, a circuit including said solenoid and a trip lever, a trip on said skip adapted to operate said trip lever as said skip is lowered to loading position to close the circuit through said solenoid for moving said four-way valve to open the gate, and a time limit relay in said solenoid circuit adapted to cause said solenoid to close said valve for closing said gate after a predetermined interval. 100 105 110

8. In an apparatus of the class described, in combination, a skip, a source of supply of material, a chute leading therefrom, an oscillating end gate on said chute, said skip having an inclined side, said gate having a spout thereon and movable with respect thereto, said spout adapted to extend within said skip under certain conditions and lie substantially parallel to said inclined skip side to direct flow of material along said skip side at an angle obtuse thereto, means for actuating said gate, and separate means for actuating said spout to vary its angle of inclination with respect to the inclined side of the skip. 115 120 125

9. In an apparatus of the class described, in combination, a skip, a source of supply of material, a chute leading therefrom, an oscillating end gate for said chute, means for op- 130

erating said gate independently of the skip for delivering material from said source of supply into said skip under certain conditions, and valved means for automatically governing the speed of operation of said operating means.

10. Skip loading apparatus, including in combination, a skip, a bin, a chute leading from said bin for discharge into said skip, an end gate for said chute, fluid pressure means for operating said gate, a spout associated with said gate so as to have vertical hinging movement with respect thereto, fluid pressure means for moving said spout, control devices for each of said fluid pressure means, said control devices being interconnected and adapted for automatic operation in a predetermined cycle after initiation, means governed by downward movement of said skip for initiating the cycle of operation of said control devices for opening said gate, moving the said spout and finally closing said gate, said last mentioned means becoming inoperative on upward movement of said skip.

11. Skip loading apparatus, including in combination, a skip, a bin, a chute leading from said bin for discharge into said skip, an end gate for said chute, fluid pressure means for operating said gate, a spout associated with said gate so as to have vertical hinging movement with respect thereto, fluid pressure means for moving said spout, control devices for each of said fluid pressure means, said control devices being interconnected and adapted for automatic operation in a predetermined cycle after initiation, means governed by downward movement of said skip for initiating the cycle of operation of said control devices for opening said gate, moving the said spout and finally closing said gate, said last mentioned means becoming inoperative on upward movement of said skip, said control device for said spout operative after said gate is closed for returning said spout to its lowest position with respect to said gate, and adapted on opening movement of said gate to permit bodily movement of said spout with said gate without affecting the angular relationship of said spout and said gate during such movement.

12. In mechanism of the class described, in combination, a skip, means for delivering material into said skip, a cut-off gate associated with said delivery means, a spout on said gate movable with respect thereto, power means for operating said gate, other power means for operating said spout, control devices for said power means adapted for automatic operation after initiation, and means controlled by movement of said skip for initiating movements of said control devices.

13. A skip loading apparatus, in combination, a skip, a bin, a chute leading from said

bin, an oscillating end gate for said chute, a spout pivoted to said gate adapted for vertical movement about its pivotal connection, fluid pressure means for operating said gate, other fluid pressure means for operating said spout, control devices for each of said fluid pressure means, means rendered effective by said skip as it reaches loading position to actuate the control device of said gate operating means for opening the gate, other means connected with said control devices and rendered effective when said gate is open to permit actuation of the spout operating means, a time limit relay included in said last mentioned means operative at a predetermined interval after said gate is opened for causing actuation of said spout operating means to raise said spout, means actuated by said spout operating means as said spout is raised to cause said gate operating means to close said gate, and means rendered effective when said gate is closed to indicate such position when permitting hoisting of said skip.

14. A skip loading apparatus, including in combination, a skip, a bin, a chute leading from said bin, an oscillating end gate for said chute, a spout pivoted to said gate adapted for vertical movement about its pivotal connection, fluid pressure means for operating said gate, other fluid pressure means for operating said spout, means actuated by said skip as it reaches loading position for causing said gate operating means to open the gate, means including a time limit relay rendered effective by the open position of the gate to raise said spout after a predetermined interval, other means effective when said spout reaches its raised position to close the gate and indicate the position of said gate for permitting hoisting of the skip, said spout operating means operative after said gate is closed for returning said spout to its lowest position with respect to said gate, and adapted on opening movement of said gate to permit bodily movement of said spout with said gate without affecting the angular relationship of said spout and said gate during such movement.

15. A skip loading apparatus, including in combination, a skip, a bin, a chute leading from said bin, an oscillating end gate for said chute, a spout pivoted to said gate adapted for vertical movement about its pivotal connection, fluid pressure means for operating said gate, other fluid pressure means for operating said spout, control devices for each of said fluid pressure means, said devices being interconnected and adapted for automatic operation in a predetermined cycle, each of said devices including a four-way valve and a solenoid for operating the valve, electric circuits including said solenoids, the solenoids of the gate operating means being included in a circuit comprising a normally closed switch which is operated by the spout

mechanism under certain conditions and set up when said skip reaches loading position for opening the gate, the solenoid of the spout operating means being included in a circuit which includes a time limit relay and a contactor, which contactor is closed by the skip reaching loading position, said time limit relay closing the circuit to said spout solenoid after a predetermined interval for raising the spout, the spout operating means breaking the circuit through the gate solenoid on reaching raised position, thereby causing actuation of the gate operating means to close the gate, a hoisting signal circuit established when said gate reaches closed position, said contact or circuit being broken as said skip is hoisted, thereby breaking the circuit through the spout solenoid, permitting the return of the spout to lowest position with respect to the gate.

16. In a mechanism of the class described, a skip, a chute for delivering material into the skip, a cutoff gate movably associated with the chute, a spout movably carried by the gate, power means for moving the gate from closed position to open position or vice

versa, this movement carrying the spout into or out of the skip, and power means for moving the spout with respect to the gate so that its angle of inclination within the skip may be varied, and means actuated by the movement of the skip for controlling the power means.

17. In a mechanism of the class described, a skip, a chute for delivering material into the skip, a cutoff gate movably associated with the chute, a spout movably carried by the gate, power means for moving the gate from closed position to open position or vice versa, this movement carrying the spout into or out of the skip, and power means for moving the spout with respect to the gate so that its angle of inclination within the skip may be varied, and means actuated by the movement of the skip for causing the power means to successively open the gate and lower the spout into the skip, elevate the spout within the skip, and then close the gate and move the spout out of the skip.
